UNITED STATES PATENT OFFICE.

THEOPHILUS F. NEILSON, OF PALISADE, NEW JERSEY.

EXPLOSION-ENGINE.

1,221,081.

Application filed January 8, 1916. Serial No. 70,936.

Patented Apr. 3, 1917.

To all whom it may concern:

Be it known that I, THEOPHILUS F. NEILSON, a citizen of the United States, residing at Palisade, county of Bergen, State of New Jersey, have made a certain new and useful Invention in Explosion-Engines, of which the following is a specification.

This invention relates to explosion engines and particularly to that type of the same which may be termed the rotary or rotating piston type.

The object of the invention is to provide an explosion engine which is simple in structure, economical to manufacture, and efficient in operation.

A further object of the invention is to provide a rotary piston type of explosion engine.

A further object of the invention is to provide an engine of the class described which may be exceedingly light in weight, but which will develop very high speed and power.

A further object of the invention is to provide an engine of the class described which may employ any type of fuel without being subjected to the disadvantage of carbon deposit within the cylinder thereof.

Further objects of the invention will appear more fully hereinafter.

The invention consists substantially in the construction, combination, location and relative arrangement of parts, all as will be more fully hereinafter set forth, as shown in the accompanying drawings and finally pointed out in the appended claims.

Referring to the drawings, Figure 1 is a broken view in side elevation, partly in section on the line 1--1, Fig. 2, of an engine embodying my invention.

Fig. 2 is a broken view in elevation of the same, partly in section, taken on the line 2--2, Fig. 1.

Fig. 3 is a diagrammatic view of the cylinder of an engine embodying the principles of my invention.

Fig. 4 is a view in side elevation of the stationary end plate of the engine employed in connection with my invention.

Fig. 5 is a view in section taken on the line 5--5, Fig. 4.

Fig. 6 is a view in side elevation of the revoluble face plate employed in connection with my invention.

Fig. 7 is a sectional view of the same taken on the line 7--7, Fig. 6.

The same part is designated by the same reference numeral wherever it occurs throughout the several views.

It is among the special features of my invention to employ rotary pistons, and to arrange the same with respect to a single stationary irregular cylinder within which they operate and with respect to each other that the spaces between the pistons may be employed for carrying on the cycles of the engine, that is, one space for the intake of fuel, one for the compression, one for the ignition and one for the exhaust thereof, all as will be more fully hereinafter explained.

In accordance with my invention I employ a main shaft 1, which is journaled in a stationary interior casing 2, the periphery of which is irregular in shape as shown in Figs. 1 and 3, and is provided with depressions 15 in its face as shown in Fig. 3. An exterior stationary casing 3, of substantially the same irregular shape as the casing 2, forms between the two casings a space 16 which forms the cylinder chamber of the engine. A shouldered ring 4 on one side of the cylinder is secured, such for instance, as by bolts 19 to the exterior stationary casing 3 to hold a shouldered ring 5 in place, which ring 5, in turn, holds the side face plate 6 in position to form journals for the rotary pistons to be hereinafter described.

On the opposite side of the cylinder, a disk 7 is secured to the casing 3, and also to casing 2, by means of bolts 20, for example, to hold the shouldered ring 8 in place, and which ring 8, in turn, holds the side face plate 13 in position to form journals for the other end of the rotary pistons.

Secured to the inner casing 2, such as by a bolt 25, is a gear wheel 9 which meshes with a gear wheel 10 keyed or otherwise suitably secured to shaft 1 of the piston, and which is journaled in a sleeve bearing 100 51 carried by the radial arms 12 which arms have a hub 50 secured to shaft 1 in any desirable manner, such as by key 23. From the foregoing it will be seen that when shaft 1 is rotated, the arms 12 rotate therewith and consequently the shafts 11 are carried rotatively thereabout, while at the same time, due to the gear wheels 9 and 10, the shafts 11 are independently rotated axially as shown.

Each shaft 11 carries a piston 25 which is preferably cam shaped as shown, and opposed to rotation by a shoulder to remain bevelled as far as possible to reduce

erates between the opposed surfaces of the interior and exterior stationary casings 2 and 3 which form the cylinder chamber of the engine. Each piston is preferably provided with a large antifriction roller 18 and a smaller antifriction roller 17 which rollers are adapted to work in contact with the surfaces of the casings 2 and 3 as shown, to reduce friction and keep the surfaces 10 clean.

It will be understood that the gear wheels 9 and 10 may be of any desired ratio, or relative size. In the construction shown, I find it preferable to employ a 2:1 ratio, so 15 that the piston shaft 11 will rotate axially three times to every revolution of the main shaft 1, and, in consequence, the piston 25 will revolve axially three times on each revolution of the shaft.

20 Referring to the diagrammatic illustration of Fig. 3, it will be seen that in this form of my invention I show four rotary pistons 25, but my invention, in its broadest scope as defined in the claims, is not to be 25 limited in this respect. It will be understood that whatever number of pistons are employed, there will be a similar number of piston shafts 11, and their associated gear wheels 9, and 10, all operating as hereinbefore described. The cam shaped pistons divide the cylinder 16 into four compartments, A, K, E, and G. In the position of the pistons shown, the fuel is being drawn into one of the compartments, say at A, which is the 30 admission chamber between pistons B' and H. Due to the eccentric shape of the cylinder 16, upon one quarter of a revolution of the main shaft the piston shown at C has drawn in the charge in back of itself and in 35 the space between the piston B and the piston C. Upon the next quarter revolution of the main shaft 1, the fuel which is in compartment K is compressed in the compartment E as the pistons advance assuming the position shown at C and D. The fuel is here ignited, causing the explosion which forces the piston at D to the position shown at H, and, due to the eccentric shape of the cylinder, the piston which was at C, 40 assumes the position shown at D, thereby allowing the fuel to expand in the compartment G, as will be readily understood. The piston at H may uncover an exhaust port, or any suitable time controlled valve may 45 allow the burnt fuel to be forced out of the compartment G, upon the third quarter revolution of the main shaft 1, which causes the piston at D to advance. It will be understood that each piston operates with respect to the piston immediately in advance of and behind it in identically the same manner as above described upon each revolution of the main shaft, thereby securing the same 50 number of explosions per revolution of the main shaft as there are pistons employed.

From the foregoing it will be seen that upon each quarter revolution of the main shaft, though each piston travels at the same speed, due to its planetary movement, its cam shape, and the irregular shape of the cylinder, the pistons travel relatively different distances, that is, one piston advances more quickly toward its preceding piston than the succeeding piston does at certain portions of the revolution of the main shaft, 75 thereby securing the complete cycle of the engine for each piston per revolution of the main shaft.

With a construction embodying my invention it will be seen that I am enabled to have a fixed inlet chamber, explosion chamber and exhaust chamber. Any suitable means may be employed to secure the proper explosion in the explosion chamber, such, for instance, as the usual spark device 21, 85 controlled in any suitable manner to secure a spark on each quarter revolution of the main shaft, all as is well known in the art. Likewise any suitable means may be employed for controlling the inlet of fuel and 90 the exhaust of burnt fuel. I show a simple arrangement wherein I provide cup shaped projections 14 on the disk 7, one for exhaust and one for the intake of the fuel. These cup shaped projections form chambers to 95 which supply and exhaust connections 52 are made. These chambers are adjacent to each other and are in communication with the cylinder 16 between the casings 2 and 3, through ports 41 of face plate 13 which 100 serves as a revolvable valve.

If desired, and as shown, at the points of greatest depression 15 of the cylinder, auxiliary antifriction rollers 30 may be employed to facilitate the movement of the 105 cam shaped pistons by those points during their planetary movement.

From the foregoing it will be seen that I have provided an explosion engine which is simple in structure and which eliminates all reciprocating parts, thereby avoiding all power losses incident thereto. It will be understood, further, that an engine embodying my invention will develop high power and speed with a light structure, without 110 any additional strain on the movable parts thereof, the structure being made of simple, standard parts, without the necessity of using packing. It further simplifies lubrication as the same may be secured by simply 115 feeding graphite or like lubricant to the surfaces of the casings 2 and 3. Further, it secures a universal rotary action in a gas engine which is obviously of great advantage, and which has heretofore, to the best 120 of my knowledge, been impossible.

It is obvious that by increasing the number of pistons in a single cylinder, and the number of resultant compartments in the cylinder, with an additional exhaust and 130

inlet port, and a spark device, for every two additional pistons employed, any desired number of explosions may be secured per revolution of the main shaft, thereby enabling a single cylinder engine embodying my invention to take the place of the present four, six and eight and twelve cylinder engines now in common use. It is evident, therefore, that great space, material and weight is saved. It is also obvious that due to the continual contact of the respective pistons on the surfaces of the cylinder, no carbon deposit is allowed to collect in the cylinder, thereby enabling any form of fuel, even crude oil, to be employed, which heretofore has been impossible.

While I have shown and described in detail a structure embodying the principles of my invention, I wish it to be understood that many changes in details will readily occur to those skilled in the art without departing from the broad scope of my invention as defined in the claims. Therefore, what I claim as new and useful and of my own invention, and desire to secure by Letters Patent, is

1. An explosion engine comprising a main shaft, a cylinder, and a plurality of rotary pistons positively secured to said shaft and adapted to rotate about said shaft in said cylinder to rotate said shaft and means to successively form compression and explosion chambers within said cylinder between adjacent pistons.

2. An explosion engine comprising a main shaft, a cylinder, and a plurality of rotary pistons positively secured to said shaft and adapted to rotate about said shaft in said cylinder to rotate said shaft and means to successively form compression and explosion chambers within said cylinder between adjacent pistons, and means actuated by the rotation of said shaft for individually rotating said pistons.

3. An explosion engine comprising a main shaft, a stationary casing in which said shaft is journaled said casing provided with a cylinder chamber extending completely circumferentially around said shaft, a plurality of rotary pistons for said cylinder and adapted to travel therein and means to successively form compression and explosion chambers within said cylinder between adjacent pistons, and means actuated by the travel of said pistons for rotating said shaft.

4. An explosion engine comprising a main shaft, a stationary casing in which said shaft is journaled said casing provided with a cylinder chamber extending completely circumferentially around said shaft, a plurality of rotary pistons for said cylinder and adapted to travel therein and means to successively form compression and explosion chambers within said cylinder between adjacent pistons, and means actuated by the

travel of said pistons for rotating said shaft, and means actuated by the rotation of said shaft for axially rotating each of said pistons about its individual axis.

5. An explosion engine comprising a main shaft, a casing surrounding the same and provided with an irregular cylinder chamber therein, a plurality of eccentrically rotatable pistons mounted in said irregular cylinder chamber to travel therein around said shaft, and means associated with said pistons and actuated by their travel for rotating said shaft.

6. An explosion engine comprising a main shaft, a casing surrounding the same and provided with an irregular cylinder chamber therein, a plurality of eccentrically rotatable pistons mounted in said irregular cylinder chamber to travel therein around said shaft, and means associated with said pistons and actuated by their travel for rotating said shaft, and means operated by the rotation of said shaft for axially rotating each of said eccentrically rotatable pistons.

7. An explosion engine comprising a main shaft, a stationary casing in which said shaft is journaled said casing provided with a cylinder chamber extending circumferentially around said shaft, a plurality of pistons for said cylinder and adapted to travel therein and means to successively form compression and explosion chambers within said cylinder between adjacent pistons, and means actuated by the travel of said pistons for rotating said shaft, and means actuated by the rotation of said shaft for axially rotating each of said pistons and antifriction means associated with each of said pistons to facilitate the axial rotation thereof.

8. An explosion engine comprising a main shaft, a casing surrounding the same and provided with an irregular cylinder chamber therein, a plurality of individually rotatable eccentric pistons mounted in said irregular cylinder chamber to travel therein around said shaft, and means associated with said pistons and actuated by their travel for rotating said shaft, and means operated by the rotation of said shaft for axially rotating each of said eccentric pistons, and antifriction means associated with each of said eccentric pistons to facilitate the axial rotation thereof.

9. In an explosion engine, the combination with a main shaft, a cylinder and a plurality of individually rotatable pistons located in said cylinder to rotate therein about said shaft, means for admitting fuel into said cylinder between adjacent pistons, means for igniting said fuel and means for exhausting said burnt gases from between said adjacent pistons and from said cylinder.

10. In an explosion engine, the combination with a main shaft, a cylinder, and a plurality of individually rotatable pistons to

- cated in pairs in said cylinder, means for admitting fuel into said cylinder between two of said pistons, means controlled by the travel of said pistons for compressing said fuel, means for igniting said compressed fuel, means operated by the ignition of said fuel for rotating said shaft.
11. In an explosion engine, the combination with a main shaft, a cylinder, and a plurality of individually rotatable pistons located in pairs in said cylinder, means for admitting fuel into said cylinder between two of said pistons, means controlled by the travel of said pistons for compressing said fuel, means for igniting said compressed fuel, means operated by the ignition of said fuel for rotating said shaft, and means controlled by the further travel of said pistons for exhausting said burnt fuel.
12. In an explosion engine, the combination with a cylinder comprising stationary irregular casings to form a circumferential irregular passage therebetween, and a plurality of individually rotatable cam shaped pistons adapted to travel circumferentially in said passage.
13. In an explosion engine, the combination with a cylinder comprising stationary irregular casings to form a circumferential irregular passage therebetween, and a plurality of individually rotatable cam shaped pistons adapted to travel circumferentially in said passage, and means operated by the travel of said pistons to cause the axial rotation thereof.
14. In an explosion engine, the combination with a cylinder comprising stationary irregular casings to form a circumferential irregular passage therebetween, the points of greatest irregularity thereof lying diametrically opposite to each other, a plurality of individually rotatable cam shaped pistons adapted to travel circumferentially in said passage, means for admitting fuel and means for igniting said fuel, both of said means being located at said diametrically opposite points of greatest eccentricity of said cylinder.
15. In an explosion engine, a stationary casing having an irregularly shaped chamber, a shaft journaled in the casing, a plurality of individually rotatable cam shaped pistons operating in said chamber, said pistons having a planetary motion about said shaft, and connected thereto to rotate the same.
16. In an explosion engine, the combination with a cylinder, of a plurality of individually rotatable pistons adapted to operate therein, and means for causing adjacent pistons to vary the distance therebetween to successively form compression and explosion chambers within said cylinder.
17. In an explosion engine, the combination with a cylinder, of a plurality of individually eccentrically rotatable pistons adapted to operate therein, and means for causing adjacent pistons to vary the distance therebetween to successively form compression and explosion chambers within said cylinder.
18. In an explosion engine, the combination with a cylinder, of a plurality of individually rotatable pistons adapted to operate therein, and means for causing adjacent pistons to vary the distance therebetween to successively form compression and explosion chambers within said cylinder, a main shaft, and means operated by the rotation of said main shaft for individually rotating said pistons.
19. In an explosion engine, the combination with a cylinder, of a plurality of individually rotatable pistons adapted to operate therein, and means for causing adjacent pistons to vary the distance therebetween to successively form compression and explosion chambers within said cylinder, a main shaft, and means operated by the movement of said pistons relative to said shaft for rotating said shaft.
20. In an explosion engine, the combination with a cylinder, of a plurality of individually rotatable pistons adapted to operate therein, and means for causing adjacent pistons to vary the distance therebetween to successively form compression and explosion chambers within said cylinder, a main shaft, and means operated by the movement of said pistons relative to said shaft for rotating said shaft, and means operated by the rotation of said main shaft for individually rotating said pistons.
- In testimony whereof I have hereunto set my hand on this 27th day of December, 105 A. D., 1915.

THEOPHILUS F. NEILSON.
